UNITED STATES PATENT OFFICE.

JAMES B. DUFF AND THOMAS W. KEATING, OF NEW YORK, N. Y.

ENVELOP-MACHINE.

Specification of Letters Patent No. 22,788, dated February 1, 1859.

To all whom it may concern.

Be it known that we, JAMES B. DUFF and THOMAS W. KEATING, of the city, county, and State of New York, have invented certain new and useful Improvements in Machinery for Pasting or Gumming and Folding Envelops; and we do hereby declare that the following is a full, clear, and exact description of the same, reference being had 10 to the accompanying drawings, making part of this specification, in which—

Figure 1 is a longitudinal vertical section taken nearly through the center of a machine with our improvements. Fig. 2 is a 15 transverse vertical section of the machine, in the plane indicated by the line α , α , of Fig. 1, as seen looking in the direction of the arrow shown near that line. Fig. 3 is a plan of all of the machine below the plane 20 indicated by the line y , y , in Fig. 1, but omitting the parts above such plane. Fig. 4 is a plan of the folders. Figs. 5, 6, 7, 8, 9, are views of separate parts of the machine, which will be hereinafter explained. Figs. 25 10 and 11, are respectively views of the blank and the folded envelop.

Similar letters of reference indicate corresponding parts in the several figures.

This invention consists in a pasting apparatus of novel character by which the pasting of the envelop on any part but where it is required is effectively prevented.

It also consists in a novel contrivance for creasing the blanks in the lines in which 35 the folds are to be produced. And it further consists in an improved construction of the lappers by which the folds are finished.

A, A, B, B, C, is the main framing of the machine, consisting of two standards A, A, 40 supporting a horizontal bed C, and stayed by stretchers B, B. At the front end of this framing, and above and extending partly over the bed C, is the feed board K, upon which the envelop blanks are placed one by 45 one by an attendant as fast as they can be taken by the feeding hooks D, D, and thereby carried to a position over the quadrangular open die E, and under the plunger F, which works through said die and carries 50 the blanks through with it, thus bending the flaps all at right angles to the center of the envelop, which bending is a preparatory stage of the folding operation.

At the two ends of the die E, and one on 55 each side of the machine are arranged boxes G, G, which contain the paste or adhesive

material used to make the parts of the envelop adhere, and in which work the pasters a, a, which dip into the paste or adhesive material and apply it to the side flaps of the 60 blanks before the plunger descends upon them. Some distance below the die E, is the folding table H, upon which the folding of the flaps is finished by four folding lappers I', I², I³, I⁴, which are upright when the 65 plunger F comes down upon the table with the blank, but which, after the plunger has risen, fall over one after the other flat upon the table, which folds the flaps down one after the other.

Behind the folding table H, there is an inclined chute J, on to which the envelops, after being pasted and folded, are deposited by the fall of said table to the position shown in Fig. 1, in red outline, and down which 75 they slide on to the floor or into a suitable receptacle, passing in their way between a pair of pressure rolls U, U, which press together the pasted and folded flaps.

We have endeavored to give, above, a general idea of the nature and operation of the principal parts of the machine, with a view to render the following more particular and detailed description more intelligible as it 80 proceeds.

The feeding hooks D, D, which take the blanks from the feed table K, are formed on the ends of two long rods D', D', which are secured to a shaft D², which works in bearings in two arms D³, D³, of a rockshaft D⁴, 90 which is arranged in fixed bearings near the bottom of the machine. One of the arms D³, D³, is connected by a rod D⁶, with an eccentric D⁵, on the main shaft L, of the machine, which works in bearings on the lower 95 rails of the standards A, A; and this eccentric, by the vibratory motion it imparts to the arms D³, D³, gives the feeding hooks the requisite motion as is illustrated in Fig. 1, where said hooks and arms are shown in black and red outline at the two extremities of their movement, and where, as well as in Fig. 2, the envelop blank is shown in blue outline on the feed board and also in red outline in the position to which it is carried by the feeding hooks. On the front part of the feed board K, there is a stop b, which prevents the feeding hooks, as they come forward, from pushing off the blank which has been placed upon the board during their advance. The said hooks are so beveled on their upper parts as to prevent them catch-

ing the blank as they move forward to fetch it. There are stops Y , Y , secured to the back part of the top of the die, to bring the blank square with the die when the hooks 5 have fed it up. The top of the die E is level with the face of the feed board, and it is while upon this die that the side laps of the blanks are pasted. We will however describe the whole of the folding apparatus before 10 describing the details of the pasting apparatus, as the movements of the latter are derived from parts of the former.

The form of the interior of the die E , of course corresponds with that which the envelop is to have when folded. The exterior of the plunger F is of the same form and sharp for the purpose of creasing the paper surrounding it. The plunger is made hollow or with a cavity in its face so that its 20 lower edges c , c , may project and be made sharp for the purpose of creasing the paper exactly in the lines where the fold is to be made by the lappers I' , I^2 , I^3 , I^4 , by forcing the latter into contact with the face of the 25 table H , which has a thick covering of india-rubber, as shown at d , d , Figs. 1 and 2, into which the sharp edges of the piston can indent themselves and thus crease the paper without cutting it. The table H is made of 30 metal and the india-rubber d , is applied to it in a sheet on the top of a thin layer of shellac, which is applied in a pulverized state to the surface of the table while the latter is hot and thus melted so that the india-rubber will adhere to it.

The plunger is attached to a rod F' , which works in guides in an upright standard F^2 , erected upon the top of the main framing, and which is prevented turning by means of 40 a crosshead F^3 , and two guide rods e , e , which are attached to the said crosshead and work in guides in the standard F^2 . To effect the vertical movement of the plunger, its rod F' , is connected with the arm M' , of 45 a rockshaft M^4 , which is arranged in bearings in the top of and near the rear of the machine, and which is furnished with another arm M^2 , to which is connected a rod M^3 , which works in fixed guides f , f , attached 50 to the framing, and which is furnished at its bottom with a friction roller f' , which bears upon a cam M , on the main shaft L . This cam—of which Fig. 5 is a view representing it detached from the machine—operates to 55 lift the piston, but its descent is effected by the aid of a strong spring f^3 , applied to its arm M^2 , in addition to its own weight and that of a weight F^4 , applied on the top of its rod.

60 The forms of the lappers I' , I^2 , I^3 , I^4 , which complete the folding process that has been partly effected by the operation of the plunger F , in combination with the die E , and the india-rubber face of the table H ,— 65 are best represented in Figs. 7 and 8, the

former of which figures represents the lapper I^2 , and the latter the lapper I^4 . The lapper I' , is precisely like that I^2 , and the lapper I^3 like that I^4 . Fig. 9 is a transverse section through the middle or operating portion of either lapper, as all are alike in their operating portions. They consist severally of flat plates attached to or made in the same piece with bent rockshafts N' , N^2 , N^3 , N^4 , whose journals g , g , work in bearings 70 h' , h' , h^2 , h^2 , h^3 , h^3 , h^4 , h^4 , secured on the top of the bed C ; said bearings being so arranged that the faces of the lappers may be brought flat down upon the paper upon the folding table H . These lappers are 80 made with square or angular edges j , at the junction of the heels i , with the faces as shown in Fig. 9, instead of round as shown in Fig. 9*, which is the usual construction, and being upright during the operation of 85 the plunger, with their edges j , j , nearly close to the table H , they combine with said table when in that position, to form a square-bottomed box; and by that means the blanks are prevented rising from the table 90 as the plunger rises therefrom, as they are very apt to do when the heels of the lappers are made round, and thus the folding of them all to a uniform size is insured. The 95 said lappers are also so constructed (as shown in Fig. 9) that when they stand upright as they do when the plunger deposits the paper on the table H , their heels i , i , will be slightly above their centers of motion, but that their faces will project slightly beyond the said centers, so that the sharp edges j , formed by the junction of the heels and faces will descend and move very slightly outward toward the edge of the table as the lappers descend to fold the flaps; and by that means the said edges are caused to pass over and off the edges of the folds and lay them very flat. The crank-like bends of the rockshafts N^3 , N^4 , is to allow those N' , N^2 , to work under them. 100 The lappers do not come down altogether, but one slightly in advance of another in the order indicated by the numbers upon them, to fold the flaps so that their edges lap each other properly. They are operated by four cams O' , O^2 , O^3 , O^4 , all of similar form, on the main shaft L , aided by four springs k' , k^2 , k^3 , k^4 . The said cams act on four levers l' , l^2 , l^3 , l^4 , which work on a fixed fulcrum shaft P and which are connected respectively with the rockshafts N' , N^2 , N^3 , N^4 , by rods m' , m^2 , m^3 , m^4 , and the said springs connect the levers with the framing of the machine in such a manner as to keep the anti-friction rollers 110 n' , n^2 , n^3 , n^4 , with which the levers are furnished, in contact with the cams. The cams open or throw back the lappers, and the springs bring them down to make the 115 fold. The partly-folded envelop is represented in Figs. 7 and 8, the

sented in blue outline in Figs. 1, 2, 3, which represent the lappers at the time of I' having completed, I^2 having nearly completed, I^3 having just commenced, and I^4 not having yet commenced, their respective operations. Fig. 4 shows the operation of all as having been completed and represents the envelop folded as in Fig. 11.

The pasting of the blank to secure the side and bottom flaps of the envelop together is only required along the lower margin r, r' of the exterior of the side flaps, which, after the folding is completed come in contact with the marginal portion of the interior of the bottom flap. When a blank arrives over the die E , its side flaps are over the two paste boxes G, G , and pasters a, a . These pasters consist each of a piece of wire or plate metal, arranged with its edge upward, and curved to the form of the margin of the side flaps of the blank. The said pasters are attached to the front ends of long levers Q, Q , which work on fulcrum pins in small standards Q', Q' , on the top of the framing. The rearmost arms of these levers, which are longer and heavier than the forward arms that carry the pasters, rest in forks p, p , provided for them on the arms D^3, D^3 , before described; and as the said arms move forward to make the feeding hooks fetch a blank from the feeding table, the said forks lift the rear ends of said levers Q, Q , and cause the pasters to descend into the paste at the bottom of the boxes to take a supply; and afterward as the said arms return to produce the feed motion of the hooks, the rear arms of said levers are permitted to descend by gravitation and raise the pasters above the top of the box. The pasters do not come in contact with the flaps by their own action, as the said flaps on the arrival of the blank over the die E , are held up by two thin elastic plates or flat springs K', K' , which are attached to the feed board and project therefrom in a rearward direction partly over the paste boxes; but the flaps are forced down into contact with the pasters by the action of two fingers s, s , at the extremities of two levers R, R , which are arranged on two stationary fulcrum pins t, t , secured in the standard F^2 . These fingers are held up out of the way of the pasters and blanks during the whole of the time occupied in feeding and folding, by means of springs t', t' , applied to the levers R, R , and only depressed momentarily during the short interval which elapses between the deposit of the blank upon the die E , and the entry of the plunger F , into said die. The momentary depression of the levers R, R , and the fingers s, s , is effected as the plunger F commences its descent, by the action of the lower toe-shaped extremities of the two guide rods e, e , on two tumblers t^2, t^2 , at-

tached by pins t^3, t^3 , to the levers; the said toe-shaped ends striking said tumblers near their extremities, and after depressing them a little way, passing them, and allowing the springs t', t' , to raise them. The levers are furnished with stops for the tumblers to rest against when the latter are depressed, but the latter are allowed to rise as far as necessary for the rods e, e , to pass them without disturbing the levers R, R , as the plunger F rises. The fingers s, s , have grooves extending the whole length of their bottom faces as shown in Fig. 2, and also in Fig. 6, which latter figure exhibits a section parallel with Fig. 1, of the pasting apparatus employed at one side of the machine, and owing to the positions of the paster and finger s , it exhibits them partly in perspective. These grooves in the bottom of the fingers s, s , must be amply wide enough to receive the pasters without the latter touching either side, and the descent of the said fingers, which takes place when the paster is raised to its highest position should be just low enough for the two edges at the sides of the grooves of the fingers to pass slightly below the upper edges of the pasters which constitute their operating faces. One edge of each finger s , occupies a position over the rear portion of the corresponding spring plate K' and the rear terminations of the spring plates are in lines parallel with and very near the pasters, so that they may pass each other; and hence as the fingers descend to press the flaps upon the pasters, they press down the spring plates at the same time, and as the fingers rise again they raise the flaps out of contact with the pasters. By this system of pasting apparatus all smearing is effectively prevented, and if the feeding hooks should miss or the machine remain in operation for any length of time without any blanks being supplied, the pasters will touch no part of the machine, but leave everything clean and thus prevent the blanks that are subsequently supplied to the machine from being pasted on the wrong side, as frequently happens with other pasting apparatus if the feed motion misses or the supply of blanks to the machine is suspended.

To provide for the falling of the folding table H , to the position represented in Fig. 1, in red outline and before referred to, for the purpose of discharging the pasted and folded envelop, the said table is secured to or cast with two stout levers S^2, S^2 , which are connected by a strong hinge-joint u , with the bottom of the bed C ; and it is connected at u' , by a rod S' , with one end of a lever S^3 , secured to a rockshaft S^4 , fitted to work in bearings in the lower parts of the standards A, A . The other end of the lever is fitted with an anti-friction roller u^2 , to be acted upon by a cam S , on the main

shaft. This cam is of the same form as the cams which operate the lappers, (one of which cams O^3 is fully represented in Fig. 1) and by its action above the lever S^3 , it holds up the table H , during the greater portion of each revolution of the main shaft, and then allows it to descend by gravitation to deposit the envelop on the upper portion of the inclined chute J . To insure 10 the removal of the envelop from the table H , two stationary fingers w, w , are attached to the framing of the machine, below said table, and are arranged to pass through slots w', w' , in the said table as the latter descends and thus to tip up the front side of the envelop from the surface of the table, which makes it certain to slip off and to be deposited on the upper part of the chute J . This chute is simply an inclined plane, but 20 it is made in two pieces with a space between them, through which the lower one of the pressure rolls U, U , presents itself to receive the envelops upon it. The lower pressure roll receives a continuous rotary 25 motion through a belt z , from a pulley V , on the main shaft L , and the upper one receives motion by its friction on the surface of the lower one or upon the envelops passing over it. The weight of the upper 30 roll must be sufficient or it must be loaded by weights or springs applied at its journals to press the envelops sufficiently to cause the adhesion of the pasted parts. It will be understood from the description of 35 the pasting apparatus that this machine does not apply the gum or gluten to the seal flap. This is applied by any suitable means to the blanks and allowed to dry before the said blanks are supplied to the machine.

40 It will be observed that by having the axes of the lappers I^1, I^2, I^3, I^4 , arranged above the level of the table, an open space is left immediately between the heels of the lappers and the surface of the tables; and 45 that when the plunger descends, the paper is bulged a little, and slightly passes under the said heels, which hold the paper and prevent it from rising or getting out of place when the plunger rises. This open 50 space is filled by the face of the lappers when they close, and the edges of the paper, which before rested under the heels, are folded flat upon the table.

In addition to the bulging of the paper 55 under the heels of the lappers, the retention of the paper in place is also assisted by the vertical faces of the lappers, against which

the paper is pressed by the plunger when it descends.

We do not claim, broadly, the invention 60 of oscillating lappers to fold envelops; nor do we claim the arrangement and combination of a half circle with the heels or base of the lappers.

We distinctly disclaim "the folding flaps 65 projecting from the center or nearly so from the end of a shaft or shafts and having their bearings on one end or on each end thereof, whether with or without the half circles,"—as set forth in the 3rd claim of Milton G. 70 Puffer's patent, Nov. 23d, 1858, and we hereby disclaim all and every part covered by said Puffer's invention.

Having thus fully described our invention, we will proceed to state what we claim 75 as our invention, and desire to secure by Letters-Patent.

1. We claim the combination of the pasters a, a , the grooved pressure fingers s, s , and the spring plates K', K' ; the whole being applied to operate substantially as herein set forth.

2. In combination with a folding table having its surface composed of india-rubber or other elastic substance, we claim the use 85 of a plunger operating through a die above the said table and provided with sharp projecting edges, for the purpose, after it has forced the blank through the die and thus turned back the flaps, of making a sharp 90 crease where the fold is to be made, by pressure between said edges and the elastic surface substantially as herein described.

3. We claim placing the faces of the lappers I^1, I^2, I^3, I^4 , in front of their centers 95 of motion, and their axes above the level of the table, as herein shown and described, so that the plunger E , when it descends shall pass close against the faces of the lappers, and the heels of the lappers, when the latter close, will move outward away from the paper, as herein shown and described.

4. We claim having an open space between the heel of the lappers I^1, I^2, I^3, I^4 , to receive and hold the edges of the paper 105 when it is pressed therein by the descent of the plunger, as and for the purposes herein shown and described.
